COLORED SCREEN FOR STEREOSCOPIC PROJECTIONS

Louis Lumière, Neuilly-sur-Seine, France

Application December 17, 1935, Serial No. 54,928
In France November 22, 1932

5 Claims. (Cl. 88—16.6)

Among the various solutions that have been proposed to the problem of producing stereoscopic images by projection on a screen, only one seems to have been put into practice to a certain extent. This solution, which was exposed by d'Almeida in a paper dated 1858 (C. R. ac. des Sciences, t. XLVII, p. 337) and which was then claimed to have been disclosed five years earlier by Rollmann (Poggendorff Annalen IXC, 1853, 10 p. 185) consists in making use of red and green rays for projecting two respective images of a stereoscopic couple and also for impressing these images on the two eyes respectively (for instance by means of screens). But this method has the 15 very serious drawback that it produces an intolerable fatigue of the eyes, due to the action on each of them of different rays which exert very different actions thereon.

It has indeed been proposed to employ other 20 couples of complementary colored screens, but none of these solutions of the problem ensures the equality of the amounts of luminous energy received by the two eyes respectively.

The object of the present invention is to provide 25 a couple of screens for use according to the method above referred to which obviate the drawbacks above mentioned.

To this effect, the screens according to my invention are so colored that both of them allow 30 red and green rays to pass therethrough but with different wave lengths so as to equalize the amounts of luminous energy received by the two eyes respectively while performing the desired discriminating action.

Examples of my invention will be hereinafter 35 described with reference to the accompanying drawing, given merely by way of example and in which:

Fig. 1 shows a curve, which will be herein-after called "curve of sensations", serving to 40 graphically illustrate an essential feature of the present invention.

Fig. 2 is a diagrammatic view of the screens according to the present invention, as mounted 45 on spectacles;

Fig. 3 is a diagrammatic sectional view of a screen according to the present invention;

Fig. 4 is a similar view of a composite screen according to the present invention;

Fig. 5 is a sectional view on the line 5—5 of Fig. 2, with the screen shown in elevation.

In the "curve of sensations", as shown by Fig. 1, the wave-lengths have been plotted in abscissas, while the ordinates correspond to the ratio of the visual effect and of the calorific

effect of the rays. This curve, which is well known in photometry, is based on the works of Gibson and Tyndall, and it reproduces the specific curve given in No. 475 of the "Scientific papers of the Bureau of Standards" in 1923, and adopted by the "International Commission on Illumination", in 1924.

According to my invention, in order to do away with the fatigue resulting from the perception by the eyes of colored rays as different as red and green rays respectively, the screens placed in front of the eyes of a spectator (in the form of spectacles or eye-glasses) and which will be respectively the same as those placed across the path of travel of the light rays that project the two images of the stereoscopic couple must comply with the following requirements:

(a) both of them must allow red and green rays to pass therethrough but with different wave lengths, and

(b) their respective regions of transparency must correspond to approximately equal portions of the area limited between the curve of sensations and the axis of abscissas.

In order to comply with these conditions, one of the screens should have a transparency as great as possible for the region $npp'n'$ ranging between $\lambda=550m\mu$ and $\lambda=640m\mu$ and the other one should permit the passage of both rays corresponding to the region $mn'n'$ ranging between $\lambda=640m\mu$ and the extreme visible red on the one hand and rays corresponding to the region pqp' ranging between $\lambda=550m\mu$ and the extreme visible violet on the other hand.

It results from this choice that the whole luminous energy received by each of the eyes is the same and that, notwithstanding the apparent colors of the screens are different, nevertheless both of them will allow red and green rays (which are those which have the most different and marked action on the eyes) to pass therethrough.

In Fig. 2, I have shown, by way of example, spectacles fitted with screens r and l according to the present invention.

I will for instance employ for the screen intended for the left projecting light beam and for the left eye a gelatinized glass in which the gelatin is colored with a mixture of naphtol green, eosin and tartrazin, the concentrations of the solutions and the periods of time for which they are allowed to act being so chosen that the absorption spectrum above stated may be obtained. In Fig. 3,

I have shown such a screen, 3 being the glass support and 4 the layer of colored gelatin.

In a likewise manner, the screen for the right projecting light beam and the right eye will be similarly obtained, but by superposing for instance a gelatinized glass in which the gelatin is colored with a solution of cyanol blue upon a second glass colored by means of a solution of saccharein of diethylmetamidophenol (because, as one of these coloring matters is an acid and the other one is a base, they combine with each other and form a precipitate when they are mixed together) and by adjusting, as for the screen corresponding to the left eye, the concentrations of the solutions and the periods of time for which they are allowed to act in such manner that the optical absorption of the whole of the two glasses may be complementary to that of the screen corresponding to that of said left eye. In Fig. 4, I have shown such a composite screen, 3' and 3'' being the glass supports and 4' and 4'' the layers of colored gelatin.

The gelatinized glasses that form the screens according to the present invention can be prepared in the well known manner which consists in placing these glasses, after cleaning them as perfectly as possible, on a plate of marble the surface of which is perfectly horizontal, and in pouring on said glasses a gelatin solution in water of 8 or 10%, at the rate of 10 cubic centimeters per square decimeter. The gelatin that is employed may be of any kind whatever, provided that it is free from fatty matters, such as gelatin being easily found on the market.

The glasses thus covered with gelatin are caused to dry as soon as the gelatin has taken a jelly-like consistency, care being taken that dust cannot reach them.

In order to obtain dyes complying with the requirements above mentioned, I may, for instance, pour onto the dried gelatinized surfaces of glasses treated as above explained the coloring solutions the formulas of which are hereinafter given, and after a suitable duration of contact, these surfaces are wiped with a very fine piece of linen, and finally they are allowed to dry.

The following formulas, given merely by way of example, permit of obtaining the desired result.

First glass.—Solution consisting of the following mixture:

Solution of tartrazine of 2%----- cm.³ 20
 Solution of eosin of 2%----- cm.³ 14
 Solution of naphtol green of 5%----- cm.³ 16

the duration of impregnation ranging between 30 and 40 seconds.

Second glass.—Solution of cyanol blue of 1%; duration of contact: about 60 seconds.

Third glass.—Solution of saccharein of diethylmetamidophenol of 5%; duration of contact: about 30 seconds.

In order to obtain the first of the two finished screens, I superimpose upon the first glass a colorless transparent glass 3a (Fig. 3) which is glued by means of Canada balsam in such manner as to protect the layer of colored gelatin, thus enclosed between two glasses.

The second screen will be obtained by gluing the second and third glasses against each other, 70 gelatin against gelatin, by means of Canada balsam.

Screens made as just above explained comply with the conditions above stated, one of them allowing only the rays of a wave length ranging 75 between 550 and 640 microns to pass therethrough

and the other screen absorbing these rays and allowing the remainder of the spectrum to pass therethrough.

In a modification, the two complementary screens are obtained by spreading upon the dry 5 gelatinized surfaces of glasses treated as above explained, the following coloring compositions:

First screen.—Solution of 2% of bright blue for wools FFR of the I. G. Farbenindustrie. This 10 coloring matter, which should preferably be employed in the pure state, was discovered recently and is not described in Schultz Tables.

Second screen.—Solution containing simultaneously 2% of pure naphtol green (No. 5 of Schultz Table of 1931) and 3% of Poirier II 15 Orange (No. 189 of the 1931 Schultz Table). This last solution is relatively weak so as to avoid crystallizations when it is being used. If a single application is not sufficient, two successive applications should be made.

The solvent that is used for preparing these two coloring solutions is preferably a mordant for gelatin and it may, for instance, consist of a mixture of equal amounts of acetic acid, water 25 and alcohol.

The coloring matters above stated have been indicated merely by way of example and it does not matter if the screens are inverted, provided that each eye is provided with a screen of the same color as that interposed across the light beam which serves to project the image that said eye must alone see.

The limits above stated for the regions of the spectrum that are to be absorbed can be slightly varied according to the coloring matters that are employed, the limits of absorption of which are always more or less blurred and also according to the composition of the light that is employed for the projection.

The conditions above stated, which characterize the present invention, can also be applied in the case of anaglyphs (Ducos du Hauron, United States Patent No. 544,666) that is to say in the case in which the images of the stereoscopic couple are projected one on the other by means of 45 white light, the images being themselves colored as are the screens in the case above explained, said images being looked at through screens placed before the eyes and having the same regions of transparency, but respectively complementary, that is to say inverted for each of the eyes as far as the chromatic absorption is concerned.

The couples of chromatic screens that have been described above may also be applied to the projection of cinematographic films the surface of which is corrugated.

Said films are projected by means of the same optical system that has been used for recording the pictures, but by providing it with the screens above described.

When devising spectacles provided with complementary screens as above described, it is necessary to protect as much as possible the eyes of 65 the spectators against reflection by the frame of the spectacles of the light rays from the image that is projected. For this purpose, it is advantageous to make use, for the spectacle, of black and matt frames avoiding these detrimental reflections 70 and, furthermore, to provide these frames with flanges or projections capable of stopping the light rays. In Fig. 5, which is a section on the line V—V of Fig. 2 with the screen r shown in elevation, frame I, which is of dark shade and pref- 75

erably of a matt material, is provided, on its external part, with a protecting flange 2.

The present application is a continuation in part of my copending application filed October 5 26, 1933, Ser. No. 695,364.

What I claim is:

1. A pair of complementary color screens for use in filtering the two images of a stereoscopic couple, one of said screens having a transparency restricted to a band of wave lengths of the spectrum ranging from approximately 550 to 640 millimicrons; and the other of said screens having a transparency restricted to two bands of wave lengths of the spectrum, one band ranging 10 approximately from 400 to 550 millimicrons, and the other band ranging approximately from 640 to 700 millimicrons, and means for supporting said screens with their axes laterally spaced for passing the light of the first mentioned band to one selected position and the light of the other two bands to another selected position.

2. A pair of complementary color screens for use in filtering the two images of a stereoscopic couple, one of said screens having a transparency restricted to a band of wave lengths beginning 15 with a portion of the green-yellow of the spectrum at one edge and continuing through a portion of the orange-red at the other edge; and the other of said screens having a transparency restricted to two distinct bands of wave lengths, the one band extending from the extreme visible 20 violet and continuing through the wave lengths of green-yellow not passed by said first mentioned screen, the other band extending from the extreme visible red and continuing through the wave 25 lengths of orange-red not passed by said first mentioned band, and means for supporting said screens with their axes laterally spaced for passing the light of the first mentioned band to one selected position and the light of the other two bands to another selected position.

3. A pair of complementary color screens according to claim 2 in which one screen consists of a plate of a transparent material having a color composed of a mixture of a five percent solution of naphthol green, a two percent solution of eosin and a two percent solution of tartrazine; and in which the other of said screens consists of a pair of superposed plates of transparent material, one plate having a color composed of a one percent solution of cyanol blue and the other plate having a color composed of a five percent solution of saccharein of diethylmetamidophenol.

4. A pair of complementary color screens according to claim 2 in which one screen consists of 15 a plate of a transparent material having a color composed of a two percent solution of bright blue for wools FFR of the I. G. Farbenindustrie, and the other of said screens consisting of a plate of transparent material having a color composed of 20 a solution containing two percent pure naphthol green and three percent Poirer II orange.

5. A device for use in connection with stereoscopic projections which comprises, in combination, a couple of transparent screens each colored 25 to allow both red and green rays to pass therethrough, but with different wave lengths, the respective absorptions of said screens corresponding to equal portions of the area limited between the curve of sensations and the axis of abscissae of 30 said curve, and means for holding said screens across the respective paths of the light beams corresponding to the images on the projection screen, said last mentioned means consisting of a spectacle frame for holding said first mentioned screens, said frame being made of a dark and matt material and forming a flange extending 35 forwardly around each of said first mentioned screens.

LOUIS LUMIÈRE.
